UNITED STATES PATENT OFFICE.

SAMUEL SHAFER, JR., OF MILWAUKEE, WISCONSIN, ASSIGNOR TO CHAIN BELT COMPANY, OF MILWAUKEE, WISCONSIN, A CORPORATION OF WISCONSIN.

CONVEYING AND DISTRIBUTING MECHANISM.

1,267,341.

Specification of Letters Patent. Patented May 21, 1918.

Application filed March 22, 1915. Serial No. 16,183.

To all whom it may concern:

Be it known that I, SAMUEL SHAFER, Jr., a citizen of the United States, residing at Milwaukee, in the county of Milwaukee and State of Wisconsin, have invented certain new and useful Improvements in Conveying and Distributing Mechanism, of which the following is a specification.

My invention relates to conveying and distributing apparatus and it has been elaborated with especial reference to being used as the delivery mechanism for the product of a concrete mixing machine. The invention, however, is capable of a wide variety of applications and uses. It has especial adaptability to apparatus in which is employed a conveying receptacle arranged to traverse an overhead support such as a swinging crane or boom, the receptacle being provided with bottom doors through which the material is discharged. A cable or its equivalent is employed for moving the conveying receptacle back and forth along the said support, and this traversing cable is employed as the means for controlling the operation of the doors of the receptacle, the arrangement and combination of parts being such that the opening of the doors to discharge the contents of the receptacle is controlled by the operation of the said cable, and the closing of the doors to put the receptacle into condition to receive and retain a charge is also controlled by the movements of the said cable.

In the accompanying drawings I have illustrated one embodiment of the invention in apparatus for receiving the product of a concrete mixing machine and for delivering it to the place where it is to be used. I do not, however, wish to be understood as limiting my invention by such illustration to the particular combinations and arrangement of parts, and use, thereby indicated. In such drawings—

Figure 1 is a side elevation of apparatus embodying my invention;

Fig. 2 is a transverse sectional view taken on the line II—II of Fig. 1.

Fig. 3 is an elevation of the opposite side of the machine from that shown in Fig. 1, the boom being broken away.

Fig. 4 is a central vertical sectional view

illustrating the parts that control the movements of the doors of the conveyer bucket, in the positions they occupy when the bucket is about to commence its outward traverse from the loading position.

Fig. 5 is a transverse sectional view taken on the line V—V of Fig. 4.

Fig. 6 is a vertical sectional view taken on the line VI—VI of Fig. 3.

Fig. 7 is a detail view illustrating the automatic throw-off devices for arresting the traverse of the conveyer bucket as it reaches respectively the ends of its travel.

Fig. 8 is a central vertical sectional view illustrating the parts that control the movements of the doors of the conveyer bucket, in the positions they occupy when the bucket is on its outward traverse.

Fig. 9 is a view similar to Fig. 8 except that it illustrates the positions of the parts the moment the lock for the bucket doors is being tripped.

In the drawings, 2 indicates a portion of a concrete mixing machine of the rotary drum type, and 3 framework located near the discharge end thereof. 4 designates a bracket supported by the framework, in which is mounted a vertical pivot 5 that carries at its lower end a casting 6 in which is supported, by a horizontal pivot 7, a crane or boom 8 that constitutes a track or way along which is caused to travel the conveying and distributing receptacle for the material delivered by the mixing drum.

This boom may be of any suitable or desired construction, that illustrated in the drawings being formed of channel bars, the flanges of which constitute the tracks for the wheels 10 of a carriage 11 from which is suspended a conveying bucket or receptacle 12. The boom is preferably vertically adjustable about its pivot 7, a cable 13 being employed for the double purpose of effecting such adjustment and also supporting the boom in an extended position. Since the means for adjusting the boom about its pivot 7 form no part of my present invention they are neither described nor illustrated in this case. The carriage 11 preferably comprises a pair of side pieces 14 suitably united and carrying the wheels 10 and links or bars 15 supporting the bucket.

- Motion is imparted to the carriage to cause it to traverse the boom or crane by means of a cable 17 which is preferably in the form of an endless chain belt or drive chain. This chain belt is supported upon a driving sprocket wheel 18 mounted so as to turn freely upon the shaft constituting the pivot 7, and another sprocket wheel 18', suitably mounted at the outer end of the boom.
- 5 10 If found desirable one or more intermediate supporting idler sprocket wheels 19 may be employed for sustaining the upper strand of the chain belt and preventing it from sagging undesirably.
- 15 The bucket 12 is preferably of the bottom-discharge type, being provided for that purpose with a pair of hinged doors 91. These I arrange to open outwardly and to them are connected links or chains 20 that
- 20 25 in turn are united with an eye bolt 21 supported in the lower end of a curved lock link 22, the upper end of which is pivoted to an arm 23 rigidly secured to an axle or cross shaft 24 mounted in the carriage 11. 25
- 25 indicates a handle secured to the shaft 24 and serving as the means by which the doors of the bucket may be opened and closed manually. The arrangement for controlling the operation of the doors thus far de-
- 30 35 scribed is one well known in the art, being described and claimed in U. S. Patent No. 605,620 to Alfred M. Acklin, and constitutes a toggle lock for holding the doors closed, and that may be easily tripped or
- 35 40 45 broken, allowing the doors to open by their own weight and that of the load which they sustain. It sometimes happens that obstructions are encountered preventing the doors being tightly closed. It has therefore been found desirable to support the eye bolt 21 yieldingly, it being surrounded by a coiled spring 26 that, yielding, prevents harm or breakage to the mechanism should a stone or other article prevent the doors properly closing.
- The chain belt cable 17 is employed to move the bucket and its carriage or trolley along the boom from the position, close to the mixer, where it receives its load, to the place
- 50 55 of discharge, and also to open the doors of the bucket for discharging its contents, and for closing the doors to put the bucket in condition to receive its charge, so that a single attendant standing upon the operator's platform of the machine can readily and accurately control all the movements and manipulations of the bucket.
- 60 65 70 75 80 85 90 95 100 105 110 115 120 125
- 27 represents a sprocket segment loosely supported upon the shaft 24 with its teeth in engagement with the links of the chain belt 17. The sprocket segment carries a contact arm or piece 29 and a gear segment 28, these parts being preferably integral and the gear segment carried by the hub of

the sprocket segment and concentric therewith. 30 represents a chain guard or stirrup supported in the frame of the trolley 11 and disposed directly over the sprocket segment 27 and operating to hold the chain in engagement with the teeth of the latter. 65 70 75 80 85 90 95 100 105 110 115 120 125

31 indicates a gear, preferably of segmental form, loosely mounted upon a pivotal support 33 in the frame of the carriage or trolley and in mesh with the gear segment 28. The gear 31 carries an arm 32 at the end of which is loosely pivoted a finger or arm 34, one end of which, 35, is weighted, and the other formed into a contact device 36, adapted to engage with an offset part or projection 37 of the arm 23. 38 indicates a stop carried by the frame of the carriage with which the contact piece 29 of the sprocket segment 27 is adapted to engage and by which the extent to which such segment may move in one direction is determined. The operation of the parts just described will now be set forth, it being assumed that the bucket is in its innermost position, that is, located adjacent to the mixing drum and below the delivery spout 39 thereof, and the parts in the positions indicated in Fig. 1.

When the bucket has been filled and it is desired to move it outward along the boom to the place where its load is to be discharged, the operator, through suitable driving mechanism, such as will be presently described, causes the lower strand or run of chain belt to move outward. This chain belt, as has been described, is in engagement with the sprocket segment 27, mounted in the bucket carriage or trolley, and the latter, which is free to turn upon its pivotal support 24, has been already rotated in one direction as far as permitted, since the contact parts 29, carried by the sprocket segment, and 38, upon the carriage, are in engagement. The outward movement of the lower run of the chain belt 17 thus causes the outward traverse of the bucket and its carriage to the place of delivery, arriving at which place the movement of the chain belt is arrested. As represented in the drawings when the sprocket segment occupies the position just described the arm 32 is brought into such position 110 115 120 125 that the push-off finger 34 lies in engagement with the end of the arm 23, or with the offset or contact projection 37 thereof, where it is held by the weight 35. The bucket being at the place of discharge and the parts still in the position indicated in full lines in Fig. 1, the operator starts the cable or chain belt 17 in the reverse direction to that just described, with the result that the sprocket segment is turned upon its shaft, the trolley and the bucket which it supports yet remaining at rest at the place of discharge. This movement of the

sprocket segment communicates motion to the gear segments 28 and 31, the arm 32 which the latter carries, and the push-off finger or arm 34; and as the latter is in engagement with the upper end of the arm 23, to which the lock link 22 for the doors of the bucket is connected, the movement of the parts just described operates to rotate the said arm sufficiently far to carry its outer end over or across the axial line of the shaft 24, thus breaking the toggle lock that holds the doors of the bucket securely closed and permitting them to quickly open under the weight of the contents of the bucket, which is thereupon discharged, the parts then assuming the position indicated in dotted lines in Fig. 1. As soon as the cable has moved far enough to effect the results just stated, its motion is again arrested. As the arm 23 moves from the position indicated in full lines in Fig. 1 to that shown in dotted lines, the projection 37 thereof comes into engagement with one of the spokes or radial arms 40 of the sprocket segment, carrying it to its extreme limit of movement in one direction, with the contact parts 29 and 38 in engagement, where, being arrested, the segment operates as a support for holding the doors from further movement outward. The movement of the gear segment just described, under the influence of the weight of the contents of the bucket as it is being discharged, will cause a slight traverse of the bucket along the boom, but this is so small in extent as to be negligible. The charge of the bucket being delivered, the bucket may now be restored to charging position, and this is effected by the operator causing the chain belt or cable 17 to be moved in a direction to draw the trolley and its bucket toward the mixing machine. The first movement of the cable or chain belt causes a rotation of the sprocket segment, this taking place before the trolley begins its inward traverse, moving the parts from the position indicated in dotted lines in Fig. 1 to the positions indicated in Fig. 4. As the sprocket segment is rotated it operates to close the doors of the bucket, bringing them to toggle-locked position, by reason of the engagement between the projection 37 and the spoke 40 of the sprocket segment. When the parts are in the position indicated in Fig. 4, the push-off finger 34 assumes the position there indicated by reason of the fact that the weighted end 35 thereof rests upon the hub of the gear 31. As the doors are being closed, and the parts are moving from the position shown in dotted lines in Fig. 1 to the position indicated in Fig. 4, the projection 37 passes the end 36 of the push-off finger 34, moving outside the latter, that is, in an arc outside said part 36, which is held inward, or toward the center about which the projection moves by the engagement of the weighted end of the push-off lever with the hub of the gear 31 just referred to. Continued rotation of the sprocket segment is arrested by reason of the engagement of the lock link 22 with the cross shaft 24, after which further movement of the chain belt operates to cause a traverse of the carriage along the track toward the mixing machine. As the sprocket segment is moving, in a clockwise direction, motion is communicated to the gear segment 28 and its arm 32 in a contra-clockwise direction. As the push-off gear and finger rotate about a center to one side of the shaft 24, and as the latter is loosely pivoted, it passes below the upper connected end of the lock link 22, allowing it to come into proper or locked position without material interference. Just before the trolley reaches the inner end of the boom the operator may stop the movement of the cable, permitting the trolley and its bucket to finish their inner run under the influence of inertia or momentum. This results in causing a turning of the sprocket segment and of the push-off devices to the positions indicated in full lines in Fig. 1, that is, with the push-off finger in engagement with the projection 37 at the upper end of the arm 23, and again ready for the outward traverse of the bucket, as has been described, whenever it may have received its charge.

I will now describe the means shown in the drawings, and which I prefer to use, for driving the cable or chain belt 17.

On the main counter-driving shaft 41 of the concrete mixing machine is secured a sprocket wheel 42 from which power is transmitted by means of a chain 43 to a sprocket pinion 44 on a horizontal shaft 45. This shaft is supported in bearings carried by the boom pivot bracket 4. A double cone casting 46 constituting the driving portion of a double friction clutch is secured to the shaft 45 and rotates therewith. Supported loosely upon the shaft 45 are the two bevel gears 47 to which are respectively secured cone sections that co-operate with the movable driving clutch casing 46. The bevel gears mesh with a bevel pinion 48 upon a vertically disposed shaft 49 that passes axially through the vertical pivot 5 of the boom and carries at its lower end a bevel pinion 50. This latter meshes with a bevel gear 51, to the hub of which is secured the sprocket wheel 18 that engages with and drives the chain belt cable 17. 52 represents the hand lever by which the operator controls the movements of the traversing cable, it being connected through a suitable train of devices with the movable element 46 of the clutch. When the handle is moved in one direction the cable is driven

in a direction to cause the bucket to be traversed outward; when moved in the other direction, to be traversed inward; and when it occupies a mid-position the clutch elements are out of engagement and the traversing cable is at rest.

By the mechanism described it is entirely feasible for the operator to control all of the movements of the bucket,—its traverse 10 backward and forward, its discharge, and its closing or restoring to charging condition—, through the proper manipulation of the hand lever 52. It is, however, often desirable to provide automatic means for limiting 15 the traverse of the bucket in each direction, stopping it when it reaches the place of discharge, and again as it comes to position to receive its load; and I will now describe the mechanism which I have devised for thus 20 limiting the movements of the trolley and bucket.

54 designates a bevel pinion engaged by the bevel wheels 47, and preferably arranged diametrically opposite the bevel pinion 48. 25 It is secured to a vertical shaft 55 on which is mounted a spur pinion 56, the latter being preferably integral with the bevel pinion 54. This spur pinion meshes with a spur gear 57, the hub of which turns freely in a 30 stationary bearing 58 provided therefor. The hub of the spur gear 57 is elongated and formed into a nut 59 with which engages a screw-threaded shaft 60, that is caused, by the turning of the spur wheel and 35 nut to be moved longitudinally, either upwardly or downwardly, according to the direction in which these parts are rotated. One end of the shaft 60, preferably the lower end, is pivotally connected with a shifting 40 lever 61 that is supported between its ends upon a pivot 62. The outer or free end of this shifting lever is forked so as to form the arms 63 in which latter are mounted relatively long adjusting screws 64. An arm 45 65 is secured to the hand lever 52 by which the driving of the cable 17 is controlled, or to the shaft on which the said hand lever is mounted, and its free end lies between the ends of the screws 64.

50 From the foregoing description, taken in connection with the drawings, it will be seen that the nut 59 is rotated whenever the traversing cable is driven, this nut operating the shifting lever 61. The screws 64 carried by 55 the latter are so adjusted that one of them comes into engagement with the arm 65 and operates the clutch to throw it into its mid or neutral position, thus disconnecting the cable from the source of power, whenever 60 the trolley approaches the inner end of the boom, that is, just as, or before, it reaches the charging position. The other adjustable screw comes into engagement with the arm 65 and through it operates the clutch to dis-

engage the cable from its source of power 65 when the bucket and trolley reach the position for discharge. By adjusting the screws 64 the respective limits of the traverse of the bucket and trolley may be accurately determined.

I employ the term "receptacle" in the following claims in a broad sense, intending thereby to include both the receptacle itself and its support; which, in the particular instance illustrated, is the trolley or carriage 75 and its supporting wheels, it being quite immaterial for many uses of the invention whether the receptacle be supported from above or below, and whether its supporting wheels be mounted in a separate trolley or 80 carriage, or connected with the body of the receptacle itself.

What I claim is:—

1. The combination of a track, a traversing cable supported so as to move parallel 85 with and adjacent to the track, a discharging receptacle supported entirely by the track and arranged to be traversed thereon by the cable—in one direction when loaded and moving to the place of discharge, or in 90 the opposite direction when empty and moving to the place of loading—the receptacle being movable on the track to a limited extent relative to the cable, means operated by the relative movement of the receptacle and 95 cable for causing the receptacle to discharge, and means carried by the receptacle and operated by the cable for positively restoring the receptacle to load-containing condition after discharge, by moving the cable in the 100 direction to return the receptacle to the place of loading.

2. The combination with a track, a traversing cable supported so as to move parallel with and adjacent to the track, a discharging receptacle supported entirely by the track and arranged to be traversed along the track by the said cable and movable along the track relative to the cable, and means for holding the receptacle in 110 load-containing condition, of means operated by the cable when it is moved in one direction, and arranged first to trip the receptacle and permit it to discharge, and then, by a further movement in 115 the same direction, to again restore the receptacle to condition to receive and hold another charge.

3. The combination with a track, a discharging conveyer receptacle supported 120 thereby, a cable independent of the receptacle and free to move to a limited extent relative thereto for causing its traverse, and means for locking the receptacle in load-containing condition, of toothed gearing intermeshing with the cable and having means to be operated thereby when it is moving independently of the receptacle, to positively 125

- operate the locking means that hold the bucket, to cause a discharge thereof.
4. The combination with a track, a discharging conveyer receptacle supported thereby, a cable independent of the receptacle and free to move to a limited extent relative thereto for causing its traverse, and means for locking the receptacle in load-containing condition, of toothed gearing intermeshing with the cable and having means to be operated thereby, when it is moving in one direction and independently of the receptacle, to positively operate the locking means that hold the bucket to cause a discharge thereof, and operated also by a further movement in the same direction to restore the receptacle to condition to receive and hold another charge.
5. The combination with a track and a conveying receptacle supported entirely thereby, of a cable for causing the traverse of the receptacle and free to move to a limited extent relative thereto, the cable being of drive chain construction, and toothed connections in engagement with the said chain cable and positively operated thereby, and having means to cause the receptacle to be discharged.
6. The combination with a track and a conveying receptacle supported entirely thereby, of a cable for causing the traverse of the receptacle and free to move to a limited extent relative thereto, the cable being of drive chain construction, and toothed gearing in engagement with the chain cable and operated thereby, having means to positively restore the receptacle to normal condition to receive a load after it has been discharged.
7. The combination with a track, a conveying receptacle supported by the track, provided with doors for closing it, and means connected with the doors by which their movements may be controlled, of a cable for causing the traverse of the receptacle, means having intermeshing connection with the cable and supported by the receptacle arranged to operate the means that control the movements of the doors, and stops carried by the receptacle for limiting the extent to which the said cable-operated means may be moved independently of the receptacle.
8. The combination with a track, a conveying receptacle supported thereby provided with doors for closing it and putting it in condition to retain a charge and toggle locking means connected with the doors by which they may be closed and held in closed position, of a cable for causing the traverse of the receptacle along the track, and means supported by the receptacle, having intermeshing connection with the cable, and free to move to a limited extent relative to the receptacle and arranged to act upon the said toggle locking means and restore the doors to closed position after they have been opened when the cable is moved in one direction.
9. The combination with a track, a conveying receptacle supported thereby provided with closing doors, and toggle locking means for holding the doors closed, of a cable for causing the traverse of the receptacle along the track, a gear element having intermeshing connection with the cable, supported by the receptacle and movable relative thereto, stops for limiting the extent to which the said gear element may be moved, and means operated by the gear element for moving the toggle locking means to permit the doors to open when the cable is moved in one direction—a further movement of the cable in the same direction being arranged, through interconnection between the said gear element and the toggle locking means, to restore the latter to locking position.
10. The combination with a track and a dumping conveying receptacle supported thereby, of a cable for causing traverse of the receptacle along the track, and means supported by the receptacle having intermeshing connection with and operated by the cable, and comprising a part arranged to move in one direction to act on the receptacle to dump it, and another part moving in the opposite direction to restore the receptacle to a position to receive a charge, the said parts operating in succession.
11. The combination with a track, a conveying receptacle supported thereby, and provided with doors for controlling the discharge of the receptacle, and toggle locking means for the doors, of a cable for causing the traverse of the receptacle, a gear element supported by the receptacle, having intermeshing connection with the cable and free to move to a limited extent relative to the receptacle, such element having means for closing said doors when being moved relative to the receptacle by the reverse movement of the cable, and means also operated from the cable for tripping the toggle lock to permit the doors to open.
12. The combination with a track, a conveying receptacle supported thereby having doors for controlling its discharge, and toggle locking means for the doors, of a cable for causing the traverse of the receptacle, a gear element supported by the receptacle and free to move to a limited extent relative thereto and having intermeshing connection with the cable, and means operated by the said gear element for causing a tripping of the toggle lock to permit the doors to open, the said gear element and tripping means being brought into operation upon a reverse movement of the cable, the tripping

means operating first to trip the toggle lock, and the gear element operating thereafter to close the doors.

13. The combination with a track, a conveying receptacle supported thereby provided with doors in its lower part for controlling its discharge, and a toggle lock connected with the doors and pivotally supported by the receptacle above the doors, of a cable for causing traverse of the receptacle along the track, a gear carried by the receptacle having intermeshing connection with the cable and loosely supported upon the same axis as that about which the said toggle lock turns, stops for limiting the movements of the said gear element whereby when it arrives at either limit of its movement relative to the receptacle motion may be communicated to the latter through it from the cable, and an arm in gear with and operated by the said gear element arranged to push over the toggle lock and allow the doors to open upon the motion of the cable being reversed.

14. The combination with a track, and a dumping conveying receptacle supported thereby, of means for restoring the receptacle to condition to receive a charge and maintaining it in such condition, tripping devices acting on the last mentioned means to permit the charge in the receptacle to be dumped, a cable of drive chain construction for causing the traverse of the receptacle along the track, a gear supported by the receptacle in mesh with the said chain cable, the gear being supported so as to be free to move to a limited extent relative to the receptacle and the means to restore and maintain the receptacle in condition to receive a charge, such means and the gear being arranged to come into engagement after the latter has been tripped and the receptacle discharged, whereby on the reverse movement of the chain cable the gear acts on said means and restores the receptacle to condition to receive a charge.

15. The combination of an elevated track, a trolley arranged to traverse the track, a conveying receptacle provided with hinged doors suspended from the trolley, a cable of drive chain construction for causing the traverse of the trolley, toggle locking means connected with the doors for holding them in closed position, and gearing supported in the trolley and free to turn to a limited extent therein, meshing with and driven by the chain cable, the said cable-driven gearing being arranged to trip the toggle locking means for the doors to permit the receptacle to be discharged upon being moved relative to the receptacle and having means operating to positively restore such toggle locking means and the doors to their respective locking and closed positions upon the cable

being moved in a direction to return the receptacle to charging position.

16. The combination of an elevated track, a trolley arranged to traverse the track, a dumping conveying receptacle suspended from the trolley, a cable of drive chain construction for causing the traverse of the trolley and receptacle, gearing supported in the trolley and free to turn to a limited extent therein, meshing with and driven by the chain cable, a guard carried by the trolley for maintaining the cable in driving engagement with the said gearing, and means actuated by the said gearing as it is moved by the cable arranged both to trip the receptacle to permit it to dump its charge, and thereafter restore it to condition to receive another charge.

17. The combination with an overhead track, a trolley arranged to traverse the track, a conveying receptacle provided with bottom, hinged doors suspended from the trolley, and toggle locking means pivotally supported in the trolley frame and connected with the doors for holding them closed, of a cable of drive chain construction for causing the traverse of the trolley and receptacle, a gear segment pivotally supported in the trolley frame on the same axis as the aforesaid toggle locking means, and free to rotate to a limited extent relative to the trolley and the toggle locking means, an arm pivotally supported in the trolley frame, gearing between the said arm and the cable-driven gear, and a push-off finger carried by the said arm and adapted to engage with the toggle locking mechanism, the said parts being arranged as described whereby on a reverse movement of the cable the arm carrying the push-off finger is caused to act on the toggle locking devices and move them to release the doors, permitting the discharge of the contents of the receptacle, and thereafter, on further movement of the cable, causes the cable-driven gear to restore the toggle locking devices and the doors to closed and locked positions.

18. The combination with a track, a conveying receptacle supported thereby, a cable for causing the traverse of the receptacle, gearing for driving the cable, and a reversing clutch device through which power is transmitted for operating the cable-driving gear, of a nut and screw in engagement therewith, gearing between the cable-driving gear and the nut and screw for causing the rotation and traverse of one of the latter, a lever operated by the last referred to traversing member provided with a bifurcated end, adjustable contact pieces supported in the bifurcated ends of the lever, and an arm through which the clutch is shifted located between the said adjustable contact pieces,

the said parts being arranged to cause the clutch to be shifted to neutral position as the receptacle reaches each limit of its traverse.

- 5 19. In a machine for delivering mixed concrete, the combination of a swinging boom, a bracket in which the boom is supported by a vertical pivot, a conveying receptacle supported upon the boom, a cable
10 for causing the traverse of the receptacle along the boom, gearing for driving the cable including power transmitting parts concentric with the said vertical pivot of the boom, a reversing clutch through which

power is transmitted for operating the said 15 cable-driving gearing, clutch-shifting means adapted to be manually controlled, a lever for also operating the clutch-shifting means, and means driven from the said concentrically-disposed cable-driving gearing ar- 20 ranged to operate the said lever and through it move the clutch-shifting means to neutral position whenever the conveyer receptacle arrives at either limit of its traverse.
